UNITED STATES PATENT OFFICE.

DONALD NOBLE, OF BRIDGEPORT, CONNECTICUT, ASSIGNOR TO THE SINGER MANUFACTURING COMPANY, A CORPORATION OF NEW JERSEY.

CLOTH-PRESSER FOR SEWING-MACHINES.

954,990.

Specification of Letters Patent. Patented Apr. 12, 1910.

Application filed October 21, 1908. Serial No. 458,784.

To all whom it may concern:

Be it known that I, DONALD NOBLE, a subject of the King of Great Britain, residing at Bridgeport, in the county of Fairfield and State of Connecticut, have invented certain new and useful Improvements in Cloth-Pressers for Sewing-Machines, of which the following is a specification, reference being had therein to the accompanying drawings.

10 My invention relates to improvements in sewing machines and has to do more particularly with such machines as are employed for ornamental stitching wherein the feed of the material is manually controlled 15 in directions inclined to each other or in curvilinear directions.

It is well understood that in the construction of ornamental stitching machines, such, for instance, as the one illustrated and described in U. S. Patent No. 821,233, dated May 22, 1906, to F. Gegauf, to which class of machines my invention is applicable, the means employed for controlling the feed of the material include a comparatively large 25 circular cloth-presser (substantially such as is designated by the numeral 55 in the above referred to patent) which is resiliently depressed and controlled to release its pressure upon the material at such time as the material is being advanced under the needle.

The object of my invention is to provide a cloth-presser with means for holding the material taut beneath the presser-foot and thereby preventing it from becoming drawn 35 or wrinkled through the action of the stitch-forming and cloth-feeding mechanism, such drawn or wrinkled condition having been the difficulty experienced in connection with the use of the earlier forms of construction 40 when operating upon materials of soft light texture.

Referring to the accompanying drawings, in the several figures of which like parts are similarly designated, Figure 1 is a top plan 45 view of my improved cloth-presser; Fig. 2, a view in cross section of Fig. 1; Fig. 3, a top plan view of the flexible cloth-presser foot; and Fig. 4, a view in cross section of Fig. 3.

50 1 is the cloth-presser provided with the usual attaching arm 2, and 3 is the cloth-presser flange on which is elastically mount-

ed the flexible ring 4 which is preferably composed of rubber. The ring 4 is of plano-convex form and is illustrated in Figs. 3 and 55 4 as occupying its normal form or shape, but when it is elastically applied to the flange 3, such application being effected by constructing the flange slightly larger in diameter than the opening in the ring, the latter 60 assumes the position and form illustrated in Figs. 1 and 2, and when the cloth-presser is resiliently forced down upon the material the ring is caused to again assume substantially the form illustrated in Figs. 3 and 65 4, and as the flat surface 5 of the ring is forced up against the wall 6 the material is stretched in every direction, owing to the ring being forced to a position of increased 70 diameter.

It will be readily understood that the plano-convex form of the ring 4 is essential for securing the greatest degree of utility but said form might be slightly changed without seriously interfering with the elastic 75 control exerted by said ring. For instance, if the surface 5 were slightly convexed or concaved, the tendency of the ring when applied to the flange would still be to assume approximately the form illustrated in Fig. 80 2, and its elastic control would not entirely disappear unless its opposite surfaces were convexed to the same extent or concaved sufficiently to endanger the stability of the ring; accordingly, I do not wish to be understood 85 as limiting my invention in this respect, as a ring of substantially plano-convex form might possess sufficient utility to meet the requirements of many classes of production.

90 What I claim is:—

A cloth-presser for sewing machines comprising a main portion provided with a flange upon which is elastically mounted a flexible ring of substantially plano-convex form, said ring being mounted so as to 95 present its convex surface to the material being stitched.

In testimony whereof, I have signed my name to this specification, in the presence of two subscribing witnesses.

DONALD NOBLE.
